(57) **CLAIM**

The ornamental design for a portable beam projector, as shown and described.

DESCRIPTION

FIG. 1 is a top perspective view of a portable beam projector; FIG. 2 is a front view of the portable beam projector of FIG. 1;

FIG. 3 is a rear view of the portable beam projector of FIG. 1; FIG. 4 is a left-side view of the portable beam projector of FIG. 1;

FIG. 5 is a right-side view of the portable beam projector of FIG. 1;

FIG. 6 is a top plan view of the portable beam projector of FIG. 1; and,

FIG. 7 is a bottom plan view of the portable beam projector of FIG. 1.

Features shown in broken lines in FIGS. 4 and 7, form no part of the claimed design.
